Application August 17, 1945, Serial No. 611,016
In Great Britain June 14, 1944

11 Claims. (Cl. 72—109)

1

This invention relates to the manufacture and use of a metal pre-form fabric or foundation fabric for buildings, which may also serve as a reinforcement, and the invention provides a fabric which is self-supporting, which can be bent to any desired shape without difficulty, which is easily connected together in sections, and which forms a permanent shuttering for a poured or sprayed concrete, cement or like material. The principal aim of the invention is to provide an alternative to the prefabricated-block type of house, or other buildings, which type requires the securing together of a number of preformed units, and results in a structure which is composite, and thereby lacking the rigidity of a unitary structure. The present invention allows of the erection of buildings in a similarly-convenient or more convenient manner, but results in a unitary in-situ-cast building.

Foundation or form fabrics for buildings are known, of which the most common examples are expanded metal and wire mesh. These, however, have the great drawback that, unless of a thickness and weight which would put them far outside the range of economic use, they are not rigid and therefore cannot support themselves. For example, if stood in a vertical plane, they would bow and sag and even distort themselves, if they did not fall down altogether. Also the sheets of material, being flexible are often difficult to manage, and the connecting together of two or more sections of such material, e. g. at the corner of a building, is an unscientific task, usually finicking to perform, and even at the best a mere "hit and miss" attempt at finding suitable adjacent areas for connection together.

The fabrics of the present invention eliminate all these disadvantages. They are of light weight, well within the range of economic use, they are rigid, and are able to support themselves in any position for use, as well as being adapted for the additional uses (e. g. as shuttering) above mentioned.

A form fabric according to this invention comprises a panel (usually of metal) having weakened areas to form fold-and-break lines at spaced intervals across it, and having parts pushed out in opposite directions to form through openings along it, the pushed-out parts being such that two overlapping panels may mate together with the corresponding parts nesting one in another whilst maintaining a through opening along them. By reason of the weakened areas, the fabric may be folded to form corners, may also be bent to curved forms, without difficulty, and may easily be severed by bending to and fro at those areas. The pushed-out parts, in addition to providing the inter-engaging nesting areas, give rigidity to the panel, to resist crushing, and also to increase the relative weak-

2

ness and easy manipulation of the weakened areas. The through holes along the panel allow of the endwise insertion of rods or studs or the like for the connection of overlapping areas together.

One practical embodiment of the invention comprises a sheet metal reinforcement member and foundation fabric having rows of close perforations at spaced points to allow of easy bending and breaking at such rows, and having parallel corrugations or flutes at spaced points, each corrugation or flute being intermittent, first to one side of the sheet and then to the other, so as to form a through passage or tunnel along the sheet. Preferably the to-and-fro parts of one corrugation are staggered, with respect to those of the adjacent corrugation at each side. Also, the sheet is perforated at each point where to-and-fro parts of a corrugation or flute adjoin, and the ends of the flute parts are cut at an angle such as to leave a transverse opening if and when the sheet is bent across the line of the corrugation at such point.

In the preferred forms of the invention, the perforations and corrugations are in alternate parallel rows, each row of perforations lying between and parallel with two corrugations. Instead of there being only one row of perforations at each fold-and-break line, there may be two or more rows. One convenient arrangement has a central row of diamond-shaped openings and on each side of it a row of triangular openings with their apices inwards.

According to another feature of the invention, in panels having side-by-side parallel rows of perforations and corrugations, the perforations are arranged so that, in each row, some of them lie in line with the perforations between the to-and-fro parts of the adjacent corrugations, so as, in effect, to provide breaking or bending lines at right angles to those rows. Also, when desired, the perforations in the fold-and-break lines and in the corrugations may be so spaced as to leave breaking or bending lines diagonally across the panel.

The invention will be more particularly described with reference to the illustrations in the accompanying drawings, wherein:

Fig. 1 is a perspective view of a portion of a panel according to one of many possible examples of the invention;

Fig. 2 is a side edge view of the same; and

Fig. 3 is an end view of the same;

Fig. 4 is a perspective view showing two overlapping panels connected together;

Fig. 5 is an end view of the joint;

Fig. 6 is a perspective view of a panel folded into zig-zag form for use as a wall reinforcement;

Fig. 7 is a perspective view showing a further use of the panels as a reinforcement and as a permanent shuttering for a wall;

Fig. 8 is a perspective view showing how a panel may be folded for use in a pillar or buttress;

Fig. 9 shows in perspective, one mode of bending the panel to a curved form, in this case a circular form, for use as a column;

Figs. 10-12 are diagrammatic horizontal sections of three walls, showing three uses of the fabric as a wall reinforcement;

Figs. 13-15 are diagrammatic perspective views showing various uses of the improved fabrics as shuttering; and

Figs. 16 and 17 are perspective views of spacing members whose use is explained below.

Referring first to Figs. 1 to 5, the improved fabric shown is of sheet metal and has rows of diamond-shaped openings 1, the closeness of which at the medial apices results in weakened lines, forming bend-and-break lines, one of which is shown by the broken line 2. Between these rows of openings 1 are interrupted corrugations 3, each of which is broken so as to have alternate portions 3a on one side of the panel, and intermediate portions 3b on the other side of the panel, as seen more clearly in Fig. 2. The result is that, viewing the sheet edge-wise, as in Fig. 3, there are through openings or tunnels along the sheet, into which may be passed rods or bars for purposes hereafter explained.

Also, the ends of the projecting corrugations are cut off at an angle so as to leave through openings 4 between adjacent ends, to allow rods to pass through, either at right angles to the panel indicated at the left-hand end of Fig. 2, or at other angles, as exemplified at the centre and right-hand end of Fig. 2. As will be seen, the rows of large openings 1 alternate with the corrugations 3, and moreover, the through openings 4 are in line with some of the diamond-shaped openings 1, so as to leave transverse weakened lines, forming bend-and-break lines, as indicated at 5 in Fig. 1. In order to lighten the weight of the panel, complementary triangular-shaped openings 6 are formed between adjacent openings 1. It will be seen that each part 3a and 3b of any one corrugation is staggered with respect to the corresponding parts in the adjacent corrugations so that, across the sheet, the resulting projections and recesses on each face alternate.

Whilst in the drawings, diamond-shaped and triangular openings are shown, many other patterns may be used, such as hexagonal and octagonal openings, or circular openings, but by preference there will be corners in the openings at the parts where they are nearest to each other. Also instead of having three separate rows of openings in each flat part of the panel, as shown, there may be one row of openings having wider and narrower parts. Instead of actual openings there may be thin portions in the panel.

As shown more clearly in Figs. 4 and 5, the panels are adapted to nest with each other when overlapping, the parts 3a in the corrugations of the upper one lying in the parts 3a in the corrugations of the lower one, whilst the parts 3b of the lower one extend upwardly into the parts 3b of the upper one. By passing a rod 7 endwise through the overlapping, inter-engaging corrugations, the panels are firmly connected together and are self-held against relative movement. Naturally, the rods 7 are of smaller diameter than the largest rod which will pass along the corrugations of a single sheet.

Referring now to Fig. 6, one use of the fabric

for the erection of a partition wall is illustrated, the fabric being folded into zig-zag form by bending on the lines 2, and having a stiffening bar 8 passing through the openings at 4. This bar is of smaller diameter than one which would pass through those openings in the directions indicated in Fig. 2.

The improved fabric may readily be bent to any desired shape or form for any desired pattern of structure, and either as an internal reinforcement only or as an external permanent shuttering. Fig. 7 shows one use of the invention as a permanent shuttering for the construction of an exterior wall, in which the fabric is bent on the lines 2 to form the outline of the wall, which is afterwards filled up with the concrete 9, and may be given a rendering 10 on the outer face. The adjacent lengths of fabric are connected together by overlapping, in the manner described with reference to Figs. 4 and 5, one such overlap joint being shown at 11 in Fig. 7. When the fabric is used as a permanent shuttering it may also be used for the attachment thereto of other parts made of the same fabric, by nesting the corrugations together and inserting rods or studs therein.

In the case of a wall having two opposite layers of the fabric, either as a double internal reinforcement or as an outer permanent shuttering, strengthening and spacing members 12 may be employed, examples of which are illustrated in Figs. 16 and 17. These may be passed endwise through oppositely placed openings 1, and then given a quarter turn so that the metal of the panel is engaged in the slots 13, whereby the stiffening members are held in position and whereby they grip the panels and hold them in the correct relative positions to support the weight of the concrete.

Fig. 8 shows how the fabric may be folded to form a reinforcement or shuttering for a pillar or buttress adjacent a wall, or for a joist or beam below a floor; whilst Fig. 9 shows the fabric bent into a circular form, for use say in a circular pillar, or in a hollow cylindrical structure such as a silo or water-cooling tower. In all these cases a flat sheet of the fabric may nest with any part of the shaped reinforcement and be connected thereto by short studs or bars entering the nesting corrugations. Also, where two layers of the fabric lie at short distances apart, they may be connected together by long U-shaped members, the limbs of which extend down into the corrugations of the respective sheets. Smaller pieces of the fabric may be folded into box-like form for use in quoins, lintols, sills and the like.

The invention lends itself to a wide variety of uses. Referring to Fig. 10, a single flat layer of fabric has a cement or similar rendering applied to each of its side faces, for example, by spraying. In the arrangement of Fig. 11 where there are two parallel sheets of the fabric, either the outer face of each may be covered with a sprayed or otherwise applied rendering, leaving the centre hollow, for a cavity wall; or the centre may be filled up with concrete or insulating material; Fig. 12 shows how the fabric of Fig. 6 may be employed by the spraying thereon of a concrete, cement or like coating, on each side face.

In Fig. 13 there is shown, in diagrammatic form, the top of a column, the adjacent ends of joists and beams, and part of an in-situ floor. By the use of this invention this structure can be made as a integral unit simply by folding sheets of the improved fabric, and connecting them together

to form the outline indicated by the broken lines, whereafter the concrete filling may be applied. The fabric remains as a permanent covering. Angle pieces may be used in corners to connect parts at right angles to each other.

The invention is also useful for the construction of hollow floors and walls. In Fig. 14 a flat sheet of the fabric 14 co-operates with a folded sheet 15 indicated by broken lines, these being connected together where they nest at the parts 16, after which the in-situ material is applied to form the joists and floor.

In Fig. 15 there is the single sheet of material 17 to which are connected the channel-shaped members 18, the upper ends of which are again connected to the smaller sheets 19 whereafter the concrete or the like may be applied for moulding.

The improved fabric can be used for light studded walling bent at any given angle to form framing to support sheets of the same material which interlock as described, the piercings or perforations acting as "key" for outside rendering or inside plastering, together with screeds.

The fabric may be sold in flat sheets or in rolls, and in any case can easily be broken up into small pieces by being bent to and fro along one of the bend-and-break lines, and may be easily bent to form corners and angles or curves.

Supporting piers or columns may be made by first breaking the sheet metal into strips along two rows of perforations, leaving an intermediate row between them; then bending at such intermediate row to obtain a right-angled channel form; and finally fitting four of such angles back to back, with intermeshing corrugations, short studs or longer rods being passed through the corrugations, to hold the angles together. Those studs may have heads or other obstructions to prevent their falling completely through the corrugations, and to facilitate their withdrawal, or they may be plain, and may be parallel-sided, or tapered.

In addition to its use as a form fabric to be encased in the applied concrete or the like, or as a permanent shuttering, it may be employed as a removable shuttering, in which case the rods or studs connecting the parts together will be arranged exteriorly of the assembly so as to be easily removed when shuttering is to be dismantled, and building paper or the like will be used to cover the inner face of the fabric to prevent the concrete keying into the openings 1.

In an example of the invention, the corrugations are spaced with their centres $1\frac{1}{2}$ " apart, they are of semi-circular section $\frac{3}{8}$ " wide, and the distance between the openings at the juncture of the forward and backward parts is also $1\frac{1}{2}$ ". The metal used is 26 gauge, the perforations are of hexagonal shape, with two sides of each hexagon parallel with the rows.

It is proposed that the sheet material be bent to shape on the site, as the structure is built up, and that the concrete, cement or other material be applied by means of a spray gun or the like.

As above stated, curved forms may be made with the improved material, eliminating corners, say at chimney breasts to prevent abrupt shadows. The fabric constitutes a self-measuring form material and can be bent and cut to shape on the site with unskilled or semi-skilled labour.

What I claim is:

1. A form fabric of a single thin sheet of metal, having rows of close perforations at spaced points

5 to allow of easy bending and breaking at such rows, and having an imperforate portion containing parallel corrugations or flutes at longitudinally spaced points, each corrugation or flute being intermittent, first to one side of the sheet and then to the other, so as to form a through passage or tunnel along the sheet.

10 2. A form fabric according to claim 1, wherein in the to-and-fro parts in one corrugation or flute are staggered with respect to those in the next corrugation or flute.

15 3. A form fabric according to claim 1, wherein there is a perforation at each point where to-and-fro parts of a corrugation adjoin, said latter perforation being at an angle to the plane of said panel.

20 4. A form fabric according to claim 1, wherein in the weakened areas and pushed-out parts are in alternate parallel rows, each row of perforations lying between and parallel with two corrugations.

25 5. A form fabric according to claim 1, wherein in the perforations and corrugations are in alternate parallel rows, each row of perforations lying between and parallel with two corrugations.

30 6. A form fabric according to claim 1, wherein there is a perforation at each point where to-and-fro parts of a corrugation adjoin, wherein there are rows of perforations side by side with the corrugations, and wherein some perforations in each row are in line with the perforations in the corrugations so as to provide transverse bend-and-break lines.

35 7. A form fabric according to claim 1, wherein in a plurality of said fabrics are in overlapping relation with the corresponding weakened and elongated areas in contact and rods for locking the same together through said pressed-out sections.

40 8. A form fabric according to claim 1, wherein in a plurality of said fabrics are in overlapping relation with the corresponding weakened and elongated areas in contact and rods for locking the same together through said pressed-out sections, said overlapping fabrics being bent into a shape which is of the general outline of the desired structure.

45 9. A form fabric according to claim 1, wherein in a plurality of said fabrics are in overlapping relation with the corresponding weakened and elongated areas in contact and rods for locking the same together through said pressed-out sections, said overlapping fabrics being bent into a shape which is of the general outline of the desired structure, said shape being filled with concrete to form a unitary structure.

50 10. A form fabric according to claim 1, wherein in a plurality of said fabrics are in overlapping relation with the corresponding weakened and elongated areas in contact and rods for locking the same together through said pressed-out sections, said overlapping fabrics being bent into a shape which is of the general outline of the desired structure, said shape a beam.

55 11. A form fabric according to claim 1, wherein in a plurality of said fabrics are in overlapping relation with the corresponding weakened and elongated areas in contact and rods for locking the same together through said pressed-out sections, said overlapping fabrics being bent into a shape which is of the general outline of the desired structure, said shape a column.
